Primary Examiner — Cathy Anne MacCormac(74) *Attorney, Agent, or Firm* — Ryan Kromholz & Manion, S.C.(57) **CLAIM**

The ornamental design for a pet toy, as shown and described.

DESCRIPTION

FIG. 1 is a perspective view of a first embodiment of our invention;

FIG. 2 is a top plan view thereof, the bottom plan view, front elevation view and rear elevation view being identical thereto; FIG. 3 is a right side elevation view, the left side elevation view being identical thereto;

FIG. 4 is a perspective view of a second embodiment of our invention;

FIG. 5 is a top plan view thereof, the bottom plan view, front elevation view and rear elevation view being identical thereto; and,

FIG. 6 is a right side elevation view, the left side elevation view being identical thereto.

The broken lines in FIGS. 1, 2, 4 and 5 depict environmental subject matter and form no part of the claimed invention.

1 Claim, 2 Drawing Sheets(56)
